CHARLES B. ANDREWS, OF HIGH BRIDGE, NEW JERSEY, ASSIGNOR TO TAYLOR-
WHARTON IRON AND STEEL COMPANY, OF HIGH BRIDGE, NEW JERSEY, A COR-
PORATION OF NEW JERSEY.

DISK ASSEMBLY FOR DISK CRUSHERS.

Application filed November 22, 1923. Serial No. 676,285.

This invention relates to and has special utility in connection with crushing or grinding machines of the disk type. Grinding disks suffer heavy wear in service and require more or less frequent replacement. Heretofore, and before my invention, this has been quite a laborious task and entailed considerable loss of time, and this is especially true of the outer disk assembly.

Objects of the invention are to simplify the replacement of grinding disks by providing an integral or one-piece locking member having elements springing therefrom whereof one abuts the outer wall of the disk head and whereof the other confronts the outer wall of the disk and is responsive to deflection to lock the disk to the head; to provide a locking annulus of substantially Z section, that is to say a ring having reverse radial offsets whereof one seats against and co-operates with the outer wall of the disk head and whereof the other is capable of more or less springing action with relation to the disk, under the engaging effort of quick-acting positive securing devices. By thus obviating the use of two or more screw threaded locking rings, or the like, as obtains under the usual practice, I simplify the disk assembly; simplify the shape of the grinding disk; and reduce the cost of manufacture.

The accompanying drawing is a sectional view of a grinding disk assembly embodying the invention, the inner disk and the feed spout being indicated in dotted lines to show the general arrangement and relation of the parts.

Referring to the drawing, the numeral 5 represents the outer disk and 6 represents its complemental head or carrying portion. The usual practice is to form the disk with a central flanged portion which is secured relatively to the head by screw threaded rings or nuts. This practice has the disadvantage that grit finds its way into the screw threads and makes it difficult to assemble and dis-assemble the parts.

According to my invention, the dish shape disk 5 has a large feed opening 7 and requires no flange. In lieu of this the outer marginal wall of the feed opening presents a substantially flat wall 8 inwardly of the bore of the disk head. This construction

obviously simplifies casting with a resultant reduction in cost.

The disk and its complemental head are relatively secured by a solid locking ring 9 of substantially Z shape in cross-section, that is to say, it is formed as a unit with inner and outer reverse radial offsets 10 and 11. The ring 9, in service, fits the feed opening of the disk head, in which position the inner offset 10 confronts the outer wall of the disk, and the outer offset 11 is in abutting relation with the outer wall of the disk head. Before the application of locking pressure there is an initial clearance between the offset 10 and the disk. This fact and the more or less inherent spring quality of the locking ring due to its peculiar construction, and dependent upon its section, provides for relative deflection of the parts, under exerted pressure, to lock or clamp the disk in a positive manner to the head. The source of pressure may be any device capable of mutual engagement with the offset 10 and the disk. I prefer, however, to employ bolts 12. The heads of the bolts are countersunk so as to be within the finished plane of the disk, and the outer ends of the bolts pass through round or elongated slots in the offset 10 and co-operate with lock nuts 13.

It will be obvious to those skilled in the art that the described disk assembly is adapted for use in both vertical and horizontal mills.

Having described my invention, I claim:—

1. An outer disk assembly for grinding mills of the disk action type, comprising, in combination, a disk, a disk head, and means for relatively securing them, said means embodying an annulus having an integral element responsive to deflection, and means for deflecting it to lock the disk to the head.

2. An outer disk assembly for grinding mills of the disk action type, comprising, in combination, a disk, a disk head, and means for relatively securing them, said means embodying a ring which fits the feed opening of the disk head and has reverse radial offsets springing therefrom whereof one abuts the disk head and whereof the other is responsive to clamping to lock the disk to the head, and means for clamping it.

3. An outer disk assembly for grinding mills of the disk action type, comprising, in

- combination, a disk, a disk head, each of said elements having a bearing portion in proximity with its feed opening, a locking ring having reverse integral flanges which 5 cooperate with the respective bearing portions, the flange which confronts the disk being initially spaced therefrom, and means tending to draw the disk into engagement with the spaced flange.
- 10 4. An outer assembly disk for grinding mills of the disk action type, comprising, in combination, a disk, a disk head, a Z section locking ring having a portion engaging the outer wall of the disk head, a portion inner- 15 lying the disk head, and a portion cooperat- ing the outer wall of the disk, and means for securing said elements in assembled relation.
5. An outer disk assembly for grinding mills of the disk action type, comprising, in combination, a disk, a disk head, a substantially Z section locking ring innerlying the disk head and whereof one terminal abuts the outer wall of the disk head and whereof 20
- the other is in spaced relation with the disk, and quick acting locking elements for securing said parts in assembled relation. 25
6. An outer disk assembly for grinding mills of the disk action type, comprising, in combination, a disk having a large central feed opening the defining wall of which has 30 apertures for the passage of securing devices, a disk head having a feed opening, and means for securing the disk to the head, said means including a locking ring which fits the feed opening of the disk head and has 35 reverse radial offsets whereof one abuts the outer wall of the disk head and whereof the other offset confronts the apertured wall portion of the disk and is initially spaced therefrom and has registering apertures, and se- 40 curing devices penetrating both sets of apertures for effecting relative clamping action of the disk and head through the me- dium of the locking ring.

In testimony whereof I affix my signature.
CHARLES B. ANDREWS.
